UNITED STATES PATENT OFFICE.

JAMES W. NELSON, OF NEW YORK, N. Y.

HYDRAULIC JACK.

No. 874,700.

Specification of Letters Patent.

Patented Dec. 24, 1907.

Application filed June 14, 1906, Serial No. 321,621. Renewed October 31, 1907. Serial No. 400,071.

To all whom it may concern:

Be it known that I, JAMES W. NELSON, a citizen of the United States, and resident of the city of New York, borough of Brooklyn, county of Kings, and State of New York, have invented certain new and useful Improvements in Hydraulic Jacks, of which the following is a specification.

This invention relates to hydraulic jacks, and particularly to double or multiple-pump jacks, wherein, through the employment of all of the pumps, power is sacrificed for speed until the ram has been raised to the point where it receives the full weight of the load, after which all but one of said pumps are rendered inoperative in order that the full power of the device may be utilized.

The subject of the present invention constitutes a different form of that general type of jack shown and described by me in a prior application, filed May 21, 1906, Serial Number 317,865, and comprises generally a multiple-pump hydraulic jack in which the plungers or pump pistons are separate and parallel to each other, and has in view, in connection with such a pump or plunger arrangement, a minimum number of valves, and a valve arrangement whereby, with the simplest possible mechanism, said valves will be under manual control to render one or all thereof inoperative for the purposes herein-after set forth.

My invention will be more readily understood by reference to the accompanying drawings, forming a part of this specification, and in which

Figure 1 is a vertical, sectional, side elevation of a jack embodying my invention. Fig. 2 is a transverse section on an enlarged scale on the line 2—2 of Fig. 1. Figs. 3, 4, and 5 are vertical sections on the lines 3—3, 4—4 and 5—5, respectively, of Fig. 2.

I have selected for the purpose of illustration a general type of horizontal jack, comprising a heavy metal shell or casing 6 having mounted in one side thereof a ram-cylinder 7 and in the other side a pump-block 8 and the pump mechanism. This shell or casing 6 may be of any desired configuration, the ram-cylinder 7 being preferably screwed into a suitable screw-threaded aperture and the bottom thereof fitting within a socket, as shown, and the pump-block 8 being provided with screw-threads at its upper end, whereby it may be inserted in a suitable pocket there-

for and firmly held in place by means of the threaded ring 9.

The shell or casing 6, therefore, as will be noted, provides a chamber 10 serving as both a reservoir for the liquid employed and for the pump operating mechanism. The latter comprises a shaft 11 extending through said chamber, with suitable bearings in the walls thereof, and provided on the outside of said chamber with a head 12 apertured for the reception of an ordinary pump handle lever (not shown) by means of which said shaft may be rocked. A block 13 is vertically slideable in suitable guides 14 14, mounted within said chamber 10, and is provided with an opening or pocket for the reception of a knuckle 15 fixed upon said shaft 11. It will be apparent that when said shaft is rocked the block 13 will be vertically reciprocated.

The block 13 carries the downwardly projecting piston or plunger rods 16 and 17 which extend into the corresponding pump-bores 18 and 19 in the pump block 8. Each of the rods 16 and 17 is provided with a head or piston, 20 and 21, respectively, which snugly fit in each of the pump bores 18 and 19, a tight joint being provided by means of any well known method of packing. These bores are preferably of different diameters, and the piston-heads 20 and 21 of corresponding diameters. In this type of jack this difference in diameter is not necessary, as it is where the pistons are arranged end-to-end, or what may be termed a "tandem" one piston projecting from the end of the other. It is well known that the object of a double-pump is to provide for greater speed in raising the ram to the point where it receives the full weight of the load, at which point one, preferably the larger, pump is rendered inoperative in order to increase the power through a decrease in the area of pressure surface under the well-known principles of hydraulics. I therefore prefer to have the piston of what may be termed the real pressure pump of comparatively small cross-sectional area, and the other of larger area in order to accelerate as much as possible the speed of the rising ram prior to its meeting the full load.

The pump bores 18 and 19 do not extend completely through the pump-block but are permanently closed at the bottoms. Parallel thereto, and extending completely through the block 8, is the bore 22, which

in the construction shown, is closed at the bottom by means of the screw-plug 23 and communicates with the ram chamber 24, beneath the ram 25, through a lateral duct 26 in the arm 27 of the block 8.

The bore 22 is straight throughout its entire length, and just above the duct 26 is contracted in size to provide the seat for the valve 28 which is preferably normally held 10 in its seat by means of a spring 29 in compression between the plug 23 and said valve. Above the valve 28, a duct 30 connects the bore 22 with the chamber 31 below the smaller piston. Above this duct 30, the 15 bore 22 is further contracted to form a seat for the valve 32, the valve 28 being provided with a stem 33 extending upward nearly but not quite to said valve 32. Above said valve 32, a duct 33 connects 20 said bore 22 with the chamber 34 below the other pump piston, and above this duct 33 said bore 22 is again contracted to form a seat for the valve 35; the valve 32 being similarly provided with a stem 36 extending 25 upward nearly but not quite to said valve 35. The valve 33 is similarly provided with a stem 37 extending into the upper and preferably enlarged portion 38 of said bore 22.

30 The shell or casing 6 is provided with an aperture or opening immediately above the chamber 10, through which said chamber may be filled and which should be large enough to permit of the removal of the piston 35 tons and other parts for repacking, repair or replacement. This opening is preferably closed by means of a screw cap 39, through which extends a rod 40 which may be moved up or down through a limited distance 40 by being screw-threaded into the said cap, rotation of said rod 40 being facilitated by means of a hand-wheel 41, or its equivalent, secured to said rod on the outside of the shell or casing 6. This rod 45 extends downwardly into the enlarged portion 38 of said bore 22 to a point slightly above or just contacting with the stem 37 of the valve 35 when the latter is in its seat.

Under normal conditions, when the block 50 13 is raised in the manner hereinbefore indicated and therewith the pump pistons 20 and 21, a partial vacuum will be formed in each of the pump chambers 34 and 31. The vacuum in the chamber 34 will, on account of the greater pressure of the liquid 55 in the reservoir 10, unseat the valve 35 and the liquid will be forced into the said chamber 34. Similarly, the vacuum in the chamber 31 will effect the unseating of the valve 32 and cause the liquid to flow into 60 said chamber 31. Upon the downward stroke of said pistons, the greater pressure on the under side of the valve 35 will seat the same and the liquid in both of the chambers 34 and 31 be forced past the valve 28

and through the duct 26 into the ram chamber 24. In this manner the ram may be rapidly raised to the point where it receives the full weight of the load. At this point, the wheel 41 may be turned, forcing 70 down the rod 40 until the valve 35 is unseated and held off its seat. Thereafter all liquid which is drawn into the chamber 34, upon the up-stroke of the piston, will, upon the down-stroke thereof, be forced back into 75 the reservoir 10, while the liquid which has been drawn into the chamber 31, the valve 32 still being operative, will be forced as before into the ram chamber and under greater pressure.

80 After the desired work has been done, and it is desired to release the liquid in the ram chamber in order to lower the ram or contract the parts for subsequent or following operation, the rod 40 is further depressed, by 85 means of the wheel 41, until first the valve 35 contacts with the stem 36 and unseats the valve 32, and second said valve 32 is sufficiently depressed to engage the stem 33 and unseat the valve 28, thus opening and holding open the entire passage from the ram chamber 24 to the reservoir 10. The liquid in the ram chamber has thus free and uninterrupted passage from the ram chamber 90 back to reservoir.

95 It will be apparent that while I have shown and described a jack in which the ram and ram chamber are located laterally of the pump block, the principles of my invention may be applied with equally satisfactory re- 100 sults to a construction of jack wherein the pump-block forms a part of the ram itself. Such construction would eliminate the necessity for a lateral duct such as duct 26, the bore 22 leading directly into the ram chamber below the pump-block, for which purpose the plug 23 would be suitably apertured.

105 It will be furthermore apparent that while I have hereinbefore referred to the device illustrated and described as being of a "horizontal" type, it being, possibly, better adapted for employment in a horizontal direction than jacks in which the ram contains the pump-block and operating mechanism, it is nevertheless true that this type of jack may 110 be used vertically as well as horizontally and with equally effective results. My invention is therefore not limited to the type of jack nor to the specific construction herein 115 shown and described.

120 Having thus described my invention, I claim as new and desire to secure by Letters Patent:—

1. In a hydraulic jack, a pump-block provided with a plurality of parallel pump-bores 125 and a fluid-passage from reservoir to ram-chamber separate from said pump-bores but communicating therewith.

2. In a hydraulic jack, a plurality of parallel pump-pistons, a passage from reservoir 130

to ram chamber separate from the pump-chambers but communicating therewith, valves in said passage, and means for holding all of said valves off their seats.

5 3. In a hydraulic jack, a plurality of parallel pump-pistons, a series of check-valves to control the flow from reservoir to ram chamber and means for positively unseating all of said valves by one operation.

10 4. In a hydraulic jack, the combination, with two parallel pumps, of a series of valves for controlling flow from reservoir to ram chamber and the first of which checks back-flow from one of said pumps only, and means 15 for positively unseating said first valve, said means being further operable to unseat all of said valves.

5. In a hydraulic jack, the combination, with two parallel pumps, of a pump-block 20 having corresponding pump bores and a separate fluid-passage from reservoir to ram chamber separately communicating with each pump-chamber, an initial inlet valve to

said passage, a final outlet valve therefrom, a valve intermediate of said pump-chambers, 25 and means for rendering inoperative said inlet valve only or all of said valves.

6. In a hydraulic jack, the combination, with two parallel and connected pump pistons, of a pump block having corresponding 30 pump bores and valves for said two pump pistons in a single valve bore.

7. In a hydraulic jack, the combination, with two parallel and connected pump pistons, of a pump block having corresponding 35 pump bores and superposed valves for said two pump pistons contained in a single bore separate from the pump bores but communicating therewith.

In witness whereof, I have signed my 40 name to the foregoing specification in the presence of two subscribing witnesses.

JAMES W. NELSON.
